GAS AND MAGNETIC TELEPHONE SYSTEM.

No. 292,857.

Patented Feb. 5, 1884.

UNITED STATES PATENT OFFICE.

JAMES HARRIS ROGERS, OF WASHINGTON, D. C., ASSIGNOR TO THE AMERICAN ELECTRO-GAS TELEPHONE COMPANY, OF NEW JERSEY.

GAS AND MAGNETIC TELEPHONE SYSTEM.

SPECIFICATION forming part of Letters Patent No. 292,857, dated February 5, 1884.

Application filed March 7, 1883. (No model.)

To all whom it may concern:

Be it known that I, JAMES HARRIS ROGERS, a citizen of the United States, residing at Washington, in the District of Columbia, have 5 invented Improvements in Gas and Magnetic Telephone Systems, of which the following is a specification.

My invention relates to a method of combining a telephonic system in which the gas or 10 other pipes of a building are used for transmitting sound-waves conveyed through the gas or air confined in said pipes with an electro-magnetic telephone of any of the usual forms adapted for the purposes of my present invention, or with such modification as may be 15 necessary to so adapt it that a person in an apartment in a building in which the gas or other pipe telephone is applied may speak through the said gas or other pipe telephone, 20 and by the use of the electro-magnetic telephone with which said gas or other pipe telephone is connected may speak to a point or points outside of the building through the usual medium of electric connections.

25 In order that the invention may be fully understood, I will proceed to describe it with reference to the accompanying drawings, in which—

Figure 1 is a sectional diagram of an apparatus adapted for carrying my invention into effect, or so much of said apparatus as it is necessary to illustrate in order to make my invention clearly intelligible to any one skilled in the art to which it appertains. Fig. 2 is a 35 diagram on a smaller scale, showing two stations or houses connected by my system.

G may represent a ground-connection; B, a battery; W W', conducting-wires.

A represents a telephonic transmitting and 40 receiving instrument, containing a diaphragm, a, susceptible to sound-waves, and acted on in the usual manner by an electro-magnet, C, and serving, when used as a transmitting-instrument, to transmit the necessary impulses 45 through the wire W.

In the preferred form of my invention shown in Fig. 1 the magnet C is hollow, and is connected with the gas-pipe D, which, extending to various apartments of the building, is provided with any desirable number of branches

furnished with transmitting and receiving instruments E, which are provided with diaphragms a', adapted to confine the gas within the pipes while permitting the passage of sound-waves between the atmosphere and said 55 confined gas. It will now appear that when a person speaks at E through the gas-telephone the sound-waves conveyed through the confined gas will act on the diaphragm a in the receiving and transmitting instrument A, the 60 sound-waves being audible not only to a person applying his ear to the said instrument A, but also causing the latter to serve as a transmitting-instrument, by means of which the message will be conveyed through the line-wire W to other points, in the manner usual 65 with electro-magnetic telephones. The gas-pipe D is connected directly with the mouth of the transmitting-instrument A, causing said instrument to serve as an automatic transmitter for the use of persons located in any apartment in the building to which the gas-pipe D may extend, and which are provided with the 70 gas-telephone transmitting and receiving instruments E.

The instrument A serves as a receiver for messages coming from points outside the building through the line-wire W, and transmits the same through the gas-pipe D to the various apartments in the building, which are provided 80 with the receiving-instruments E.

The above-described apparatus is found to operate successfully under favorable conditions; but to insure its more perfect working under less favorable conditions I employ a microphone-transmitter, as shown at T, introduced in the same circuit, and having its mouth-piece in communication with the interior of the gas-pipe. This transmitter may be, in other respects, of usual construction, and does 85 not require a more detailed description.

The operation of the invention will be more fully understood by reference to the diagram Fig. 2, which shows two buildings, each provided with my gas-telephone system, and connected by line-wires, which may form a communication between two buildings simply, or may go through a telephone exchange or central office in the ordinary manner. A person speaking at E' or A' in one building may be 95 100

heard by one at the other point, and the sound-waves also communicate with the transmitter T in the same building, which transmits the message through the line-wire W to the other building, where it is heard directly at the receiving-instrument A² in the second building, or is transmitted therefrom through the gas-pipes D² to the receiving and transmitting gas-telephone instruments E² in various apartments of the second building. A conversation may be carried on between the points A' and E' through the gas-pipes D' in one building without the intervention of the electric telephone apparatus. In like manner a person at A² or E² in the other building can carry on a conversation with one in another apartment of the same building through the gas-pipes therein, while by the combined intervention of the gas-pipes and the transmitter T or T² a person in either room of the building can converse through the ordinary electro-magnetic-telephone system with one in another building or at any distant point.

S represents a call-bell adapted to be actuated by the impulses of the confined gas through a transmitter, T, by breaking the contacts of said transmitter. The operation is as follows: When desiring to signal from the gas-telephone E to the receiving and transmitting instrument A, the diaphragm a of the gas-telephone may be agitated, as by tapping, and by this means momentarily break the contacts in the transmitter T and ring a call-bell arranged to be operated by this breaking of the circuit.

Other suitable electro-magnetic call-signals may be employed for the same purpose, or a call-bell actuated directly by the impulses of the confined gas may be used. Such a one is shown and described in Letters Patent No. 251,465, dated December 27, 1881.

Having thus described my invention, what I claim as new therein, and desire to secure by Letters Patent, is—

1. The combination, with two or more electro-magnetic telephones connected in circuit, of a gas or other pipe and gas-telephones, consisting of diaphragms stretched or placed over suitable apertures in said pipe or in pipes connected therewith, so as to confine the gas or aeriform fluid in the pipe or pipes, while permitting the passage of sound-waves, and causing said sound-waves to act upon the diaphragm of the electro-magnetic-telephone instrument, substantially as herein set forth.

2. The combination, with a gas or other pipe or pipes provided with gas-telephone receiving and transmitting instruments, as described, of a diaphragm acted on by vibrations in the gas or aeriform fluid confined in said pipes, and an electric circuit closed and broken by the vibrations of said diaphragm, and serving to actuate an electric or other call signal, substantially as set forth.

3. The combination of a pipe or pipes containing gas or aeriform fluid, an electro-magnetic receiving and transmitting instrument having a hollow magnet, through which sound-waves in the fluid of the pipes will act on the telephone-diaphragm, and a second electro-magnetic receiving-instrument connected in circuit with the first, substantially as and for the purposes set forth.

4. The combination of a system of pipes containing gas or aeriform fluid and provided with gas-telephone receiving and transmitting instruments, with a system of electro-magnetic-telephone receiving and transmitting instruments connected in circuit and adapted to receive sound-vibrations from the pipes, as and for the purposes set forth.

J. HARRIS ROGERS.
